**INJECTION PUMP FOR INTERNAL
COMBUSTION ENGINES**

Kurt Froehlich, Emil Grieshaber, and Milton Leichtfuss,
Milwaukee, Wis., assignors to Nordberg Manufacturing
Company, Milwaukee, Wis., a corporation of Wisconsin

Application April 13, 1953, Serial No. 348,468

13 Claims. (Cl. 123—139)

This invention resides in the field of fuel pumps or fuel injection apparatus and mechanism and is an improvement over prior pumps which are adapted to inject various types of fuel.

More specifically a primary object of this invention is an injection pump of the dual fuel variety with means for selectively using the pump for the injection of either pilot oil or diesel fuel oil.

Another object is a pump of the above type which is adapted to inject a constant quantity of fuel at a variable time in the engine cycle or a variable quantity of fuel at a predetermined time in the engine cycle.

Another object is a fuel pump adapted to displace a constant quantity of fuel at a variable time in the engine cycle under one set of desired operating conditions and under another to displace a variable quantity of fuel beginning at an approximately constant or fixed time in the engine cycle.

Another object is an injection pump of the plunger variety which is adapted to be used on the cylinders of an engine to inject quantities of fuel that can be standardized or equalized for all of the cylinders.

Another object is a fuel pump of the plunger variety adapted to displace a constant quantity of pilot fuel at a variable time in the engine cycle, the quantity for each cylinder of the engine being standardized or equalized by a variable capacity reservoir within the pump, and the pump being further adapted to inject a variable quantity of diesel fuel beginning at a constant time in the engine cycle.

Other objects will appear from time to time in the ensuing specification and drawings in which:

Figure 1 is a vertical sectional view with parts broken away illustrating this invention as applied to a pump of the plunger variety;

Figure 2 is a development of the surface of the pump plunger shown in Figure 1;

Figure 3 is a sectional view taken along line 3—3 in Figure 1;

Figure 4 is a sectional view taken along line 4—4 in Figure 1;

Figure 5 is a vertical sectional view similar to Figure 1 and depicting a modification of this invention;

Figure 6 is a development of the pump plunger shown in Figure 5;

Figures 7 through 10 are perspective views partly in section showing the various positions of the plunger shown in Figure 5 during its operating or fuel injecting cycle; and

Figure 11 is a sectional view along line 11—11 in Figure 5.

In Figure 1 we have shown a dual fuel pump with a housing 10 which encloses a barrel 12. A plunger 14 is mounted conveniently within the barrel and is adapted to reciprocate therein. The housing 10 defines a fuel chamber 16 which surrounds the upper end of the barrel and which has an appropriate number of suitably disposed ports 18 communicating with the central bore of the bar-

2

rel. Suitable inlet connections, indicated generally at 20 are provided for the entrance of the fuel and are connected to the fuel chamber 16 in an appropriate manner. A control sleeve 22 is positioned around the lower end of the barrel and plunger and has a gear ring 24 adjacent its upper edge which meshes with a control rack 26 in a well-known manner. The lower end of the control sleeve has a rectangular or closed portion 28 which mates or coacts with a similar portion 30 on the plunger, so that any rotation imparted to the sleeve by the rack will also be imparted to the plunger. The plunger is biased downwardly by a conventional spring 32, which engages a plate 34 affixed to the lower end of the plunger. The plunger structure in the above-described mechanism is retained within the housing by a plunger guide 36 and snap ring 38.

The plunger is reciprocated by a cam 39 on the cam shaft in a conventional manner.

A delivery valve holder 40 is removably secured to the top of the housing by any conventional means and has a delivery valve 42 and its operating spring 44, the top of the holder being provided with a coupling 46 which connects the pump to a suitable outlet 48.

In Figure 2 we have shown a development of the surface of the plunger in Figure 1, this surface being primarily composed of two portions or helixes 50 and 52. The helix 50 is adapted to inject pilot fuel only when the engine is being operated on a fuel such as natural gas for example, whereas the helix 52 is adapted to inject fuel oil which may be ignited by the temperature of compression, which is not the case with natural gas. The helix 50 has a leading edge 54 and a trailing edge 56, which are essentially the port closing and port opening edges of the helixes. It should be noted that these two edges are substantially parallel and are adapted to coact with the openings 18 in the barrel, so that at any setting of the rack 24, the reciprocation of the plunger with the helix 50 in alignment with ports will result in the injection of a constant quantity of pilot fuel. The port closing edge 54 is slanted so that the time of the beginning of injection during the upward movement of the plunger may be varied. Thus this helix is adapted to inject at all times a constant quantity of pilot fuel but at a variable time in the engine cycle.

The helix 52, on the other hand, has similar leading and trailing edges 58 and 60 respectively. However, the leading or port closing edge 58 is substantially horizontal or approximately parallel to the top surface of the plunger, while the trailing or port opening edge 60 forms a continuation of the trailing or port opening edge 56 for the pilot fuel helix. Consequently, the helix 52 will inject variable quantities of diesel fuel but the injection will begin at approximately the same time in the engine cycle.

Thus we have a plunger surface with two helixes thereon, one helix being adapted to inject pilot fuel at a variable time during the engine operation but always a fixed quantity and, the other helix being adapted to inject diesel fuel beginning at a constant or fixed time during the engine operation but a variable amount or quantity, depending upon the selective positioning of the rack 26.

Due to the inaccuracies in machining and generally throughout the entire manufacturing process, the pilot fuel injection helix have been found to vary slightly from one pump to another and it has been very difficult to standard or equalize the quantity of pilot fuel that is being injected from each of the pumps on the cylinders of an engine, it being understood that one such pump will be used with each cylinder. It is the rule, rather than the exception, that one pump will inject a slightly different quantity of pilot fuel than another. Consequently, a multi-cylinder engine will operate somewhat irrationally,

To counteract this, we have provided in the delivery valve holder 40 a displacer piston 62 which is in communication with the bore of the barrel by an orifice 64. A manually variable stop mechanism 66 is positioned above the displacement piston and has an abutment 68 on the lower end thereof which can be differentially positioned with relation to the displacer piston by rotation of the stop mechanism 66. The piston is biased downwardly by a suitable spring 70, it being understood that the manually adjustable stop mechanism 66 is suitably threaded or otherwise adjustably secured in the holder 40.

Thus by proper regulation of the spring 70 during the initial portion of the upward movement of the plunger, the displacer piston will move upwardly until it strikes the abutment 68 and during this upward movement fuel will not be pumped past the delivery valve. As soon as the piston engages the abutment, the remainder of the plunger stroke will effect the normal fuel injection process. By manual or automatic adjustment of the stop mechanism, the quantity of fuel retained in the chamber of the movable displacer piston may be varied and as this quantity is subtracted from the total quantity of fuel in the barrel, the quantity of fuel injected may be accurately and precisely regulated and determined.

The upper portion of the displacer piston chamber is in communication with the main fuel chamber by a suitable passage 72 to prevent the creation of a vacuum behind the displacer piston.

The orifice 64 is substantially smaller in area than the piston chamber and gives a dampening effect to the oil moving into and out of the piston chamber.

In Figure 6 a development of the helixes of the plunger of Figure 5 is shown and it will be noted that these helixes are similar to but vary in certain respects from the Figure 2 development. To begin with, in Figure 2 there is only one set of helixes which coat with the port. However, in Figure 6, we have shown two sets of helixes which are substantially identical with each other. Each of the sets of helixes has one helix 74 for pilot fuel injection and another helix 76 for diesel fuel injection, the port closing and opening edges for the pilot fuel helix being substantially parallel; whereas, for the diesel fuel helix 76, the port closing edge is substantially horizontal and the port opening edge is disposed at a decided angle and is oriented generally in the direction of the edges on the pilot fuel helix. Thus the plunger in Figure 5 is adapted to inject a fixed quantity of pilot fuel at a variable time in the engine cycle and also to inject a variable quantity of diesel fuel beginning at a fixed time in the engine cycle.

In Figures 7 and 8 we have shown the barrel and plunger during the injection of diesel fuel, and the ports 78 are closed and opened by the helix 76, it being understood that a helix coats with each port. Figure 7 depicts the upward movement of the plunger just prior to the closing of the ports 78 and Figure 8 shows approximately the upper limit of the plunger movement after the port opening edge has passed the ports. Figures 9 and 10 show the same plunger as in Figures 7 and 8, however, it has been rotated by the rack to inject pilot fuel and helixes 74 are positioned to close and open the ports 78. The port closing is delayed, as shown in Figure 9, during the upward movement of the plunger and the port opening occurs much sooner, as shown in Figure 10. The Figure 5 plunger also varies from the Figure 1 plunger in that pressure release is effected through the tapered channel 80 between the two helixes; whereas, the Figure 1 plunger requires a central bore or hole 82.

The displacer piston 84 in Figure 5 is removed substantially from the plunger and barrel and communicates with the chamber through an opening 86, the upper portion of the piston chamber being in communication with the oil chamber through another passage 88. An abutment 90 is also provided for this piston and is adapted for manual or automatic adjustment by any conventional

mechanism shown generally at 92. The piston is biased downwardly by a spring 94 the tension of which can be adjusted by the adjustable mechanism 92. The opening or passage 86 gives the same dampening effect to the moving oil as set forth with reference to orifice 64 in the modification of Figure 1.

The use, operation and function of the invention are as follows:

Conventional engines are adapted to operate on the dual fuel principle, meaning that under certain conditions natural gas will be drawn into the cylinders, and compressed. However, the elevated temperature gained by compression of the gas is not sufficient to ignite it, consequently, a pump is generally provided to inject what is termed pilot fuel or pilot oil. The same engine may be operated on diesel fuel, which means that air is drawn in and compressed in the cylinders and toward the later part of compression, sufficient diesel fuel is injected into the cylinders to effect combustion and the ensuing power stroke expansion.

We have designed a fuel injector pump which is basically similar to conventional pumps. However, our pump is designed to inject either pilot fuel or diesel fuel, the pilot fuel, when used, being injected at a variable time but in a fixed quantity, and the diesel fuel, when used, being injected beginning at a fixed time during the engine cycle but in a variable quantity.

The Figure 1 injector pump represents a pump with a large plunger diameter and a short stroke and Figure 5 shows a pump with a small plunger diameter and a long stroke.

The Figure 1 injector pump is being used with a four cycle engines, the Figure 5 pump with two cycle engines.

Because the camshaft of the four cycle engine runs half the speed of the crankshaft, usually the cam rise per degree of crankangle is less on four cycle engines than on two cycle engines which leads to a relatively shorter stroke of the fuel pumps on four cycle engines.

Note in Figure 1 that the angle of the port closing and port opening edges on the pilot fuel helix are not as steep as the closing surfaces of the pilot fuel helix in Figure 6, this being caused by the short stroke for the Figure 2 four-stroke cycle plunger and the long stroke for the Figure 6 two stroke cycle plunger. In Figure 2, as the angle of the edges is not so steep, the two helixes can be joined together. However, in Figure 6, due to the steep angles required, the two helixes must be separated so that a satisfactory operating range can be acquired for both the diesel and pilot fuel injection.

Due to the slight inaccuracies in the plunger helixes, inaccurate quantities of pilot fuel will be injected from one pump to another. To standardize the pumps for all of the cylinders on an engine, the displacer pistons on all of the pumps can be adjusted, so that the quantity of pilot fuel injected by each of the pumps will be approximately the same. Even though we have shown the displacer piston adjusting mechanism as being manually operable, it should be understood that this mechanism could be automatically or semi-automatically accomplished.

Whereas we have shown, and described a preferred form of our invention and one modification thereof, it should be understood that various other alterations and substitutes can be made which would not depart from the fundamental theme of the invention and we desire that our invention be unrestricted except by the appended claims.

We claim:

1. For use in a fuel injection system, a fuel pump comprising a housing defining a fuel chamber with a fuel inlet and outlet, a plunger movably mounted within said housing and adapted to reciprocate therein so as to displace fuel from the chamber to the outlet, the plunger having a helixed surface opposed to the inlet, means for rotating the plunger so as to present different parts of

the helixed surface to the inlet, and means for regulating the capacity of the chamber so as to vary the quantity of fuel discharged to the outlet, said last-mentioned means comprising a variable capacity reservoir, said reservoir being in communication with the chamber through a restricted dampening orifice.

2. In a fuel pump, a housing defining a fuel chamber with the fuel inlet and outlet, a plunger movably mounted within the housing and adapted to reciprocate therein so as to displace fuel from the chamber to the outlet, means on the plunger for regulating the quantity of fuel injected including at least two helixes which coact with the inlet, one helix being adapted to inject an approximately constant quantity of fuel at a variable time during the plunger's movement and the other helix being adapted to inject a variable quantity of fuel, and means for regulating the capacity of the chamber so as to vary the quantity of fuel injected, said last mentioned means including a variable capacity reservoir in communication with the chamber through a restricted orifice.

3. In a fuel pump, a housing defining a fuel chamber with the fuel inlet and outlet, a plunger movably mounted within the housing and adapted to reciprocate therein so as to displace fuel from the chamber to the outlet, means on the plunger for regulating the quantity of fuel injected including at least two helixes which coact with the inlet, one helix being adapted to inject an approximately constant quantity of fuel at a variable time during the plunger's movement and the other helix being adapted to inject a variable quantity of fuel, and means for regulating the capacity of the chamber so as to vary the quantity of fuel injected, last said means including a variable capacity reservoir in communication with the chamber, and damping means in the line of communication between the reservoir and the chamber so as to dampen the flow of fluid therethrough.

4. In a fuel pump, a housing defining a fuel chamber with a fuel inlet and outlet, a plunger movably mounted within said housing and adapted to reciprocate therein so as to displace fuel from the chamber to the outlet, and means on the plunger including at least one helix to displace fuel from the plunger to the outlet, a variable capacity reservoir in communication with the chamber adapted to receive a variable quantity of fuel during only the initial effective portion of the plunger's pumping stroke, and damping means between the reservoir and the chamber adapted to dampen and restrict the flow of fuel between the chamber and reservoir.

5. In a fuel pump constructed for supplying liquid fuel to a dual fuel engine or the like, a housing defining a fuel chamber with fuel passages including an inlet and outlet, a plunger adapted to reciprocate in the chamber of the housing to displace fuel, that has entered the chamber from the inlet, to the outlet, means on the plunger for regulating the quantity of fuel displaced, including at least two helices disposed to coact with one of the passages, one helix being constructed to inject an approximately constant quantity of fuel at a variable time during movement of the plunger, the other helix being constructed to inject a variable quantity of fuel, means for rotating the plunger so as to selectively bring different portions of the helices into cooperative relationship with the said one passage, the helices being arranged, relative to each other, so that the position of maximum retard of the said one helix is relatively adjacent the position

of the minimum fuel delivery of the said other helix, the helices being constructed so that the quantity of fuel injected by the said one helix, in any cooperative position with the said one passage, is less than the quantity of fuel injected by the said other helix, in any cooperative position with the said one passage.

5 6. The structure of claim 5 further characterized in that the said other helix is constructed and arranged to inject a variable quantity of fuel at an approximately 10 constant time during the movement of the plunger.

15 7. The structure of claim 5 characterized by and including means for regulating the capacity of the chamber so as to regulate the quantity of fuel displaced to the outlet, including a variable capacity reservoir in communication with the chamber, the maximum capacity of the reservoir being substantially less than the capacity of the chamber, the variable capacity reservoir being constructed to regulate the capacity of the chamber so as to vary the quantity of fuel injected by the plunger.

20 8. The structure of claim 7 further characterized by and including means for regulating the capacity of the reservoir so as to vary the quantity of the fuel injected.

25 9. For use in a fuel injection system for an engine or the like, a fuel pump comprising a housing defining a fuel chamber with a fuel inlet and outlet, a plunger movably mounted to reciprocate in the housing to displace fuel from the chamber to the outlet, the plunger having a helixed surface, means for rotating the plunger so as to make different parts of the helixed surface effective so as to displace variable quantities of fuel from the chamber to the outlet corresponding to each load on this engine, and movable means for regulating the capacity of the chamber to vary the quantity of fuel discharged to the outlet for all loads on the engine, said means being unaffected by the rotary position of the plunger, said movable means including an adjustable stop mechanism for positively regulating the position of extreme movement of the movable means.

30 10. The structure of claim 9 further characterized in that said last mentioned means includes a variable capacity reservoir in communication with the chamber.

35 11. The structure of claim 10 wherein said reservoir includes a spring biased piston.

40 12. The structure of claim 11 wherein said stop mechanism is manually operable so that it may be differentially positioned with respect to the piston to determine the capacity of the reservoir.

45 13. The structure of claim 10 further characterized by and including a fluid flow dampening orifice between the variable capacity reservoir and the chamber.
